CLAIM

The ornamental design for a jewelry clasp as shown and described.

DESCRIPTION

FIG. 1 is a perspective view of a jewelry clasp according to the present design.

FIG. 2 is a top view of FIG. 1.

FIG. 3 is a bottom view of FIG. 1.

FIG. 4 is a right side view of FIG. 1.

FIG. 5 is a left view of FIG. 1.

FIG. 6 is a front view of FIG. 1.

FIG. 7 is a rear view of FIG. 1; and,

FIG. 8 is a right side view of the jewelry clasp in an open position.

The broken line portions of the jewelry clasp form no part of the claimed design.
